United States Patent Office.

JOHN MORAN, OF WASHINGTON, DISTRICT OF COLUMBIA.

Letters Patent No. 94,627, dated September 7, 1869.

STOVE-GRADE.

The Schedule referred to in these Letters Patent and making part of the same.

To all whom it may concern:

Be it known that I, JOHN MORAN, of Washington, in the county of Washington, and District of Columbia, have invented a new and useful Improvement in Stoves; and I do hereby declare that the following is a full and exact description of the same, reference being had to the accompanying drawings, and to the letters of reference marked thereon:

This invention relates to an improved device for raising and lowering the grates in stoves; and consists in the employment of a jacket, by means of which the gear-wheels and rack-bars are connected and kept always in contact with each other.

In devices for performing this kind of work, it has been found that the effect of the heat to which they are exposed has been to cause the operating parts to separate from each other, so that in a little time the entire apparatus is useless. To remedy this fault, I provide the jacket b^3 , which closely unites the gear-wheels and racks, and prevents their separation.

The details of construction of the jacket, and its connection with the other parts, will be fully described hereinafter.

Figure 1 represents a perspective view of a stove to which my invention is applied;

Figure 2 represents a side view of the cogs and gear-wheels; and

Figure 3, a front view of the same.

In the drawings—

A represents an ordinary cooking-stove.

a represents a grate of any desired form, to the bottom of which is attached the bent arms a^1 .

a^2 represents a line of cogs, attached, as shown, to the bent arms a^1 .

B represents a shaft, supported in suitable bearings

in the sides of the stove A , one end of which passes through, as shown at b , and is made square in form, for the purpose of receiving the crank x , by which means the shaft is operated.

b^1 represent gear-wheels, which engage with the cogs a^2 .

b^3 represents a jacket, of suitable shape, which passes around the cogs a^2 , both ends being attached to the shaft.

By this arrangement the cogs are kept in contact with the gear-wheels, and the amount of friction is rendered very small. At the point b^4 , in the jacket b^3 , a portion is cut away, for the purpose of allowing the cogs to rise as high as possible. A pin, a^3 , prevents them from being raised high enough to be disengaged from the gear-wheels.

C represents a ratchet-wheel upon the shaft B , outside of the stove, with which the pawl c' engages. By this means the grate is retained in any desired position.

I do not claim the idea of raising and lowering the grates of stoves by means of gear-wheels and rack-bars, for this I know to be old; but

Having thus fully described my invention,

What I claim as new, and desire to secure by Letters Patent, is—

The jacket b^3 , arranged upon the shaft B , and surrounding the rack-bar a^2 , in the manner and for the purpose described.

This specification signed and witnessed, this 14th day of February, 1868.

JOHN MORAN.
